UNITED STATES PATENT OFFICE.

WILLIAM H. ROBERTS, OF DETROIT, MICHIGAN, ASSIGNOR TO THE ROBERTS BRASS MANUFACTURING COMPANY, OF DETROIT, MICHIGAN, A CORPORATION OF MICHIGAN.

PRIMING-CUP FOR V-TYPE ENGINES.

1,170,993.

Specification of Letters Patent.

Patented Feb. 8, 1916.

Application filed April 19, 1915. Serial No. 22,450.

To all whom it may concern:

Be it known that I, WILLIAM H. ROBERTS, a citizen of the United States of America, residing at Detroit, in the county of Wayne 5 and State of Michigan, have invented certain new and useful Improvements in Priming-Cups for V-Type Engines, of which the following is a specification, reference being had therein to the accompanying drawings.

10 The invention relates to priming cups for use on explosion engines, and has for its object the obtaining of a simple construction applicable to the V-type of motors.

In the drawings: Figure 1 is an elevation 15 of the cup as applied to the cylinder; and Fig. 2 is an enlarged section thereof.

In the present state of the art, priming cups are usually formed of a plug valve having an upward extension forming the 20 cup or receptacle and a downwardly-extending threaded nipple for attachment to the engine cylinder. Such a construction is applicable to a vertical type of engine, but if placed upon a V-type of motor this would 25 incline the cup so as to spill the contents. On the other hand, if the cup is formed to extend at an angle to the valve body, so as to remain in upright position, the difficulty and cost of manufacture is increased. With 30 my improvement I have obtained a construction in which the priming cup, valve casing and nipple are all axially alined, and at the same time the mouth of the cup will be arranged in a horizontal plane when the 35 axis is inclined to be parallel with that of the V-type motor.

In detail, A is the body of the fitting having the cross tapering bore for reception of the plug B, which is held to its seat, 40 preferably by a spring C upon the projecting shank D, held by a washer E and cotter pin F.

G is a threaded nipple on one side of the body A, and H is an oppositely-projecting 45 portion, all being axially alined. The portion H is, however, cut off at such an angle to the axis that it will be in a horizontal plane when the cup is applied to the cylinder. This portion is also recessed at I

to form a recentacle which communicates 50 through the axle port J with the plug port and alined port K in the nipple. To secure the maximum capacity for the cup or receptacle I, with the minimum external diameter, the portion H is preferably of 55 spherical form.

As before stated, the threaded nipple, the body portion and the portion H are axially alined. This is highly desirable, as it allows 60 the operations of machining, polishing or buffing to be very readily performed. Thus by making the center of the spherical portion H in axial alinement with the longitudinal axis of the body portion when the article is placed in a buffing machine and 65 rotated, the portion H will have its path of rotation concentric with the path of rotation of the body portion, allowing the buffers to readily operate upon the article. After the finishing operation the portion H 70 is cut off at the desired angle and then recessed.

The construction as above described may be as cheaply manufactured as the ordinary priming cup designed for a vertical 75 cylinder, and also occupies a minimum of space.

What I claim as my invention is:—

A priming cup comprising a plug valve body portion, a nipple portion on one end 80 of said body portion and an extension on the opposite end of the body portion of substantially spherical form, said body portion and nipple portion having an axial passage therethrough, and the center of said 85 substantially spherical extension being in alinement with the longitudinal axes of said body portion and nipple portion, said extension being cut away in a plane at an angle to the axes of the body portion and 90 nipple portion, and recessed to form a cup communicating with the axial passage.

In testimony whereof I affix my signature in presence of two witnesses.

WILLIAM H. ROBERTS.
